UNITED STATES PATENT OFFICE.

JAMES F. ATWOOD, OF BOSTON, MASSACHUSETTS.

BUTTON.

SPECIFICATION forming part of Letters Patent No. 297,740, dated April 29, 1884.

Application filed October 8, 1883. (No model.)

To all whom it may concern:

Be it known that I, JAMES F. ATWOOD, of Boston, in the county of Suffolk and State of Massachusetts, have invented a new and useful Improvement in Buttons, of which the following is a specification.

This invention relates to that class of buttons provided with shanks, when said shanks, which may be solid or hollow, do not consist of wire loops, sometimes termed "shanks."

The object of this invention is to so perforate said shanks as to accommodate a wire fastening in such manner that said fastening will not be liable to break or crumble in use.

The ordinary perforation in the shank of this class of button—used largely as a trousers-button—consists of a straight hole, evenly bored, and of equal diameter throughout. This leaves, necessarily, a square edge, so that the sharp bending of the wire tends to crumble and break it. My improvement is intended to obviate this difficulty.

In the accompanying drawings, in which similar letters of reference indicate like parts, Figure 1 is a view in perspective of a button embodying my invention. Fig. 2 is a vertical section of the same. Fig. 3 is a similar view with a portion of the fastening-wire in position.

A represents the body of the button, and B the shank. The shank is perforated at C in such manner and shape that the portion of the shank which forms the under side of the perforation is convex in shape, as shown in Figs. 2 and 3, so that when the wire E is drawn tightly through said perforation and against the portion of the shank beneath it, (as it would be when the button was fastened by

said wire to a garment, and especially when there was a strain upon it, as in the case of 40 suspenders on a trousers-button, for example,) there will be no sharp bend formed in the wire, but a gradual curve, as shown in Fig. 3. The portion of the button next the top of the perforation C may be straight or 45 curved, as desired.

In order to provide space for the wire E, opposite vertical grooves, D, are formed in the sides of the shank B, leading from the foot or outer end of said shank to the perforation C, 50 as shown.

Having thus fully described my invention, what I claim, and desire to secure by Letters Patent, is—

1. The herein-described button, provided 55 with the shank B, said shank being provided with the lateral perforation C, the opposite mouths or ends of which deepen or curve downward toward the outer end of said shank, as shown, thus causing the portion of the 60 shank forming the bottom of the perforation to be convex in shape, whereby a wire fastening may be applied without causing a sharp bend therein, substantially as and for the purpose set forth.

2. The herein-described button, provided 65 with the shank B, said shank being provided with a lateral perforation and with opposite vertical grooves, D, leading from the foot or outer end of the shank to said perforation, 70 substantially as and for the purpose described.

JAMES F. ATWOOD.
